UNITED STATES PATENT OFFICE

2,347,177

VACUUM CLEANER

Dewey M. Dow, Toledo, Ohio, assignor to Air-Way
Electric Appliance Corporation, Toledo, Ohio, a
corporation of Delaware

Application October 9, 1939, Serial No. 298,608

3 Claims. (Cl. 183—51)

This invention relates to vacuum cleaners and more particularly concerns a construction for such devices seeking to reduce the operating noises generated by the suction creating unit and the passage of air into and from the filtering unit. This invention also contemplates as a means to aiding the reduction of the noise a completely new embodiment of the means and method of organizing a filtering unit and mode of suspending same from the handle of the cleaner.

The elimination of noise in any device or appliance having a rotating element and especially in those devices having parts that rotate at comparatively high speeds is very essential. When working out the problem in stationary devices it is very materially simplified in that rubber mountings can be extensively employed and in many instances the entire machine may be encased in a sound proofed housing. When it comes to portable devices a vastly different situation is presented in that lightness of the appliance or device is a necessary concomitant of the sound proof characteristics or sound absorbing devices built into the appliance or device.

Bearing the latter views in mind, the applicant has developed a light, efficient and inexpensive sound proofing or sound absorbing device for a vacuum cleaner. The problem was complicated in the instant case by reason of the fact that the disposable type of bag prevented the use of devices built permanently into the bag.

The object of this invention is to construct a vacuum cleaner in which the operating noise of the cleaner is materially reduced.

Another object of this invention is the production of a silencing device which is capable of being employed in connection with a porous paper type of filtering unit.

A still further object of the invention is the construction of a vacuum cleaner having a sound proof outer support for a filtering unit employing a porous paper dust separator.

A further object of the invention is the construction of a cleaner in which the sound absorbing or muffling means enables the withdrawal of the dust filter without disturbing the sound absorbing or muffling means and in which the sound absorbing or muffling means and dust filter while in cooperative relation to each other are not disposed one within the other.

A still further object of the invention is to construct an outer support for a dust filter which, while enabling the employment of a paper dust separator in connection with a sound absorbing or muffling means, still enables the elimination of the sound.

A still further object of the invention is the production of an outer support for a paper dust

separator which suspends the outer cover from the machine by a single pivot construction and in which the paper bag may be removed without disturbing the pivotal mounting of the outer cover or support.

A still further object of the invention is to provide an outer support for a paper dust separator which is hinged at one end or near one end of the cleaner handle enabling the outer support to swing clear of the paper bag to thereby facilitate its removal.

Other and still further objects are to sound proof the outer cover or support, its mountings relative to the handle and the suction creating unit.

Other and still further objects of the invention will appear, as the description proceeds, to those skilled in the art to which this invention appertains. While the drawings set forth the preferred embodiments of the invention and the more desirable modifications thereof, such disclosures are not to be taken as limitations of the invention but any and all modifications, variations and alterations coming within the spirit and scope of the invention are intended to be included within the invention, which is limited only by the appended claims. That which is deemed the preferred embodiment and the modifications are set forth in the appended specification and in drawings in which:

Figure 1 is a general elevational view of a vacuum cleaner embodying the invention.

Figure 2 is a view showing the filter with a portion of one of the side walls folded back to show the paper filter in position.

Figure 3 is a section taken along the line 3—3 of Figure 1.

Figure 4 is a section view taken along the line 4—4 of Figure 3 but showing the paper bag inflated.

Figure 5 is a sectional elevational view of the means for supporting the filter assembly from the upper end of the handle.

Figure 6 is a sectional elevational view showing the coupling whereby the filtering unit is attached to the fan outlet.

Figure 7 is a section view taken substantially along the line 7—7 of Figure 1.

Figure 8 is a modification of the structure shown in Figure 3 but with the sides shaped to follow the contour of the paper bag.

Figure 9 is a side elevational view of a modification of the filter organization shown in Figures 1 and 2.

Figure 10 is a section view taken along the line 10—10 of Figure 9.

Figure 11 is a fractional end elevational view of the filter shown in Figure 9 showing the inlet to the filtering unit.

Figure 12 is a view similar to Figure 7 showing

the method of holding the outer support in position of the modification of Figure 9.

Figure 13 is a view similar to Figure 10 but showing a modification of the structure in which a portion of side is hinged and taken along the line 13-13 of Figure 16.

Figure 14 is a view similar to Figure 13 but showing the outer support in a closed position.

Figure 15 shows a detail of the locking means for keeping the hinged portion of the modification of Figure 13 closed.

Figure 16 is a fractional side elevational view of the modification of Figures 13 and 14.

Numerals 1 designates generally a portable type of vacuum cleaner. The cleaner consists of a floor tool device 2 comprising a nozzle device 3 which is vertically adjustable by means of mechanism similar to that shown and described in U. S. Patent No. 2,102,221, owned by the assignee hereof. A rotary agitator (not shown) is rotatably mounted in the mouth of nozzle 3 which is driven by a motor 4 disposed above the floor tool and belt connected to the agitator. Power is supplied to motor 4 from the fan motor terminals by means of conductor 5. A rubber bumper 6 is placed about the nozzle 3 to prevent any possible injury to it or to articles of furniture or interior trim in the home.

Extending rearwardly from the nozzle 3 is the exhaust outlet 7 to which the suction creating unit 8 and handle 13 and filter 20 are swivelly connected by means of a coupling device 16 similar to that shown in U. S. Patent No. 1,900,435 wherein the functions and purposes of the construction are detailed.

The suction creating unit comprises a motor or prime mover which drives a fan (not shown) disposed in housing 12. Means have been provided whereby suction produced by the fan and motor unit is directed to either the nozzle 3 or to the hollow handle 13. This means comprises a valve structure 14 shown in greater detail in U. S. Patent No. 1,345,550. Fan housing 12 has the valve housing 16 superposed thereon and carries the valve 14. The valve housing has an extension 18 into which the connecting tube or element 17 is clamped, the other end of which tube is swivelly held in the coupling 16.

The upper end of the valve housing has an extension 18 into which the handle 13 is clamped. Disposed immediately below the handle extension 13 is the fan discharge outlet 19 which also receives the bag coupling hereinafter described in greater detail. It is evident therefore that the fan will discharge air through opening or extension 19 whether coming from the handle 13 or the floor tool 3 depending upon which way the valve 14 is set.

Suspended beneath the handle 13 is the filter unit 20. This unit is held pivotally to the switch unit 21 at its one end and its opposite end is fixed about the extension 18 of the fan case 12. The filtering unit consists of an inner paper filter 21 which is of the same general construction as that shown in U. S. Patent No. 1,970,190. Paper filter 21 is covered or surrounded by an outer support 22 made from an impervious flexible material. In order that the outer cover may be maintained in a shape similar to that shown in Figure 3, there are arranged at each end of the filter unit 20 elements 23 and 24 which are peripherally flanged and equipped with clasps or snap fasteners 25, the cooperating portion of the clasp or snap fastener being arranged in the edge of the outer support cover 22. In order that the

upper portion of the outer cover 22 may be maintained in a taut or stretched condition, there is disposed a rod 26 extending between plates 23 and 24. A rod 27 is similarly disposed between the plates 23 and 24 in the lower part of the filter unit which serves the same purpose as rod 26. Each of the rods are secured in the plates 23 and 24 and are held in position by castle nuts 28, 28, etc. Also secured to the plate 24 by a securing means 29a is a knob structure 29, preferably made of rubber, which cooperates with a slideable lever or bracket 30 for holding the upper end of the filter unit 20 in position. A more detailed description of how bracket 30 operates may be had by referring to U. S. Patent 1,905,059.

The opposite end of the filter, in which plate 23 is arranged, is fitted onto extension 19 of the fan housing. Plate 23 has an aperture as at 33 over which the plate 31 is fitted. The latter plate also has an aperture 34 and a flange 35 integral therewith. Means are provided whereby there is no sound or vibrations transmitted from the suction unit 8, said means comprising a rubber element 36 fitted into the aperture 34. The rubber element which is tubular in shape has a flange 37 integral therewith which flange abuts the plate 31 adjacent the opening 34. The rubber element prevents the transmission of the sounds and vibrations aforesaid. Means must also be provided whereby the lower end of the filter may be attached to the extension 19. To this end a second tubular element 38 which is flanged as at 39 is adapted to cooperate with the rubber element 36 and the flange 37 of tubular element 38 abuts the flanged portion 37 of rubber element 36. The aperture 40 of element 38 is adapted to be coaxial with the opening in extension 19 of fan case 12.

The mode of attachment of the lower end of the filter unit to the extension 19 is shown in detail in Fig. 7. The extension 19 is reduced in outside diameter at its end portion as indicated at 41 over which portion the end of tubular element 38 fits. Tubular element 38 has aperture 42 (Fig. 6) therein which cooperates with a threaded aperture 43 in extension 19. A screw 44 is inserted therein which holds the tubular element in place. Diametrically disposed to the screw 44 is a thumb screw 45 which is held relative to the extension 19 by a bracket 46 secured thereto by a screw means 47 as shown. There are suitable apertures provided in the tubular element 38 and in the extension 19 to receive the threaded end of the thumb screw which aids to hold the tubular element in position. The thumb screw may be threaded into the extension 19 if so desired. A further purpose of the screw 45 will be described in connection with the holding of the bag coupling in position.

Paper filter 21 has coupling 48 assembled thereto which is similar in construction to that shown in U. S. Patent No. Re. 18,962. The end of the coupling projecting from the paper bag has a groove 49 in it and since this end of the coupling 48 is inserted into the opening 40 to hold it in position, the end of thumb screw 45 engages with the groove 49 aforesaid and prevents any relative axial motion of the bag coupling and the extension 19.

The outer cover 22 of the dust collector 20, as has been previously indicated, is impervious to air. Air escaping from the fan through the outlet extension 19 and from the paper bag creates the greater quantity of noise and the silencing of this noise is one of the purposes of

this invention. To this end there is arranged in the dust collector 20 a means whereby the air may escape from the collector very quietly. The outer cover 22 is not only impervious to air but it is also sound resistant. The discharge air is led out to the atmosphere through a tube 50 arranged in the dust collector 20 as shown in Fig. 4. The tube 50 has at its inner end an elbow 51 leading into the space occupied by the paper bag. Air also finds its way into the tube 50 through auxiliary inlets 52, 52, etc., arranged therein. Surrounding the tube 50 is a mass of highly porous sound proofing material 53 which deadens the sound of the air escaping from the dust collector through the tube 50. The outer cover 22 completely enfolds the tube and its sound proofing material to make a compact maneuverable structure. In order that the sound proofing material may be kept about tube 50, a pervious cover 60 is assembled above the material 53 which keeps it about the tube 50.

Figure 8 shows a slightly modified form of the dust collector construction. The parts are related in exactly the same manner and some parts bear primed numbers. It will be observed that in the construction involving Figures 1-7 that the sides of the dust collector 20 fall straight from the upper portion leaving the bag a substantial amount of space and in fact unsupported over certain of its areas. In the modified form of Figure 8 the end plates supporting the cover are formed in a manner such that the outer cover 22' will substantially assume the shape of the inflated paper filter 21' as shown. More of the surface of the paper bag 21' will be supported thereby adding to the life of the bag.

In each of the modifications the outer cover is capable of being opened and closed. In the specific instance the outer covers 22 and 22' are provided with a zipper means 54 and 54' whereby the outer cover may be opened for the removal of the paper bags. The bags are removable by loosening the thumb screw 45, then removing the coupling 48 from the fan exhaust extension 19 and thence bodily removing the bag from the outer cover. By a reverse process another bag may be reassembled in the outer cover.

Figures 9, 10, 11 and 12 show a modification of the outer cover construction. The handle, paper bag, bag coupling and silencing devices have exactly the same relationship toward each other as in Figs. 1-7. Only the variations in structure and function will now be discussed.

The outer cover 55 of the dust collector unit 56 comprises a rigid metallic structure preferably made of a material such as a thin gauge aluminum or magnesium alloy and lined with rubber 81, or other sound proofing material. The cover 55 has end walls 58 and 59. A part of the end wall 58 has assembled thereon the connections 35, 37' and 38' for connecting the opening in the cover to the fan discharge extension 19'. The relationship of these parts is as previously discussed.

The cover in this instance has a single hinge 60 located at the upper end of the dust collector 56. The lower part 62 of the dust collector is adapted to drop away from the upper part 63 which is rigidly attached to the fan discharge and to the switch element 64, although a construction similar to that shown in Fig. 5 previously discussed might also be employed. The lower part 62 of the cover is by reason of the

hinge 60 adapted to fall away from the upper part 63 thereby enabling the bag 66 to be removed in the manner previously discussed. The upper part 63 of the cover 56 has an offset portion 67 into which the lower part 62 of the cover frictionally fits to keep the two parts in assembled relation. To provide additional support for the bag a coarse mesh bag holder 68 may be suitably hung from the side walls of the cover 55.

10 The lower part of the cover part 62 has a holding means 69 above the sound proofing material, enclosing tube 50', for retaining same in position. Auxiliary means for keeping cover part 62 in position consists of a spring pressed lock 10 which engages an appropriate shoulder 71 fixed to plate 68 and which is actuated by a push button device 12. The parts of the filter such as 15 the sound proofing and silencing units function similarly to that described in connection with 20 Figs. 1-7.

Figures 13-16 show a further modification of the cover device. In this instance the same rigid assembly as in Figs. 10-12 is employed with the provision of a cover device that is hinged along the side of the dust collector. This hinged cover portion 73 is hinged to the dust collector 74 at 75. The collector at its upper portion has an offset 76 with which the portion 73 frictionally engages to hold the cover in the locked position. 25 An auxiliary coarse mesh bag support 77 for the paper bag 78 is suitably hung from the dust collector and cover respectively. The device functions similarly to that of Figures 9-12 and the collector 74 is also lined with a sound proofing material as shown.

30 That which is considered new, novel and useful and which it is sought to protect by Letters Patent of the United States is as follows:

35 1. A vacuum cleaner filter unit cover comprising a pair of end plates, each of said plates having means thereon to mount the same on said cleaner; means extending between said plates to maintain them in a spaced relationship; an impervious cover fitted over said plates and removably secured thereto; closure means on said cover; and means to discharge air from said cover, said means comprising a tube connected to the atmosphere and surrounded by a porous sound absorbing material.

40 2. In a vacuum cleaner dust collecting cover organization; said cover having sound resistant and air tight walls forming a chamber; means on said cover adapted to permit access to said chamber and sound muffling means to discharge air from said chamber, said means including a perforated tube connected to the atmosphere and surrounded by porous sound absorbing material adapted to freely conduct air to said tube.

45 3. In a filter enclosure assembly for a vacuum cleaner; outer supports on said assembly having means thereon to support same on said cleaner; rigid means extending between said supports; a sound resistant means extending between and over said supports and having a closure means

50 55 60 65 70 thereon, said supports and said sound resistant means forming a chamber; means to discharge air from said chamber, said means including a tubular element disposed within the chamber and said tubular element surrounded by sound proofing material to muffle the sound of air escaping from said chamber.

DEWEY M. DOW.
